UNITED STATES PATENT OFFICE.

EDGAR D. MARTIN, OF CHICAGO, ILLINOIS, ASSIGNOR OF ONE-HALF TO FRANKLIN P. SMITH,
OF CHICAGO, ILLINOIS.

REISSUED

BUILDING CONSTRUCTION.

No. 872,954.

Specification of Letters Patent.

Patented Dec. 3, 1907.

Application filed January 7, 1907. Serial No. 351,048.

To all whom it may concern:

Be it known that I, EDGAR D. MARTIN, a citizen of the United States, a resident of Chicago, in the county of Cook and State of Illinois, have invented certain new and useful Improvements in Building Construction, of which the following is a full, clear, and exact description.

My invention relates to certain new and useful improvements in building constructions and more particularly to improvements in building constructions of that class, which are composed of a combination of concrete and reinforcing metal.

One of the objects of this invention is to cheapen the cost of construction of buildings of this class.

Another object is to simplify the construction and erection thereof.

Another object is to increase the strength and durability of the building without necessarily increasing the amount of material.

Another object is to lighten constructions of this class without materially reducing their carrying capacities.

Another object is to provide a structure in which the girders or horizontal supporting beams are dispensed with throughout the entire structure.

To such end this invention consists in certain novel features of construction and arrangement, a description of which will be found in the following specification, and the essential features of which will be more definitely pointed out in the claims appended hereto.

The invention is clearly illustrated in drawings furnished herewith, in which

Figure 1 is a view partly in vertical section and partly in side elevation of two columns and a fragment of a floor supported thereby, the line of section being indicated at 1—1 in Fig. 3. Fig. 2 is a plan view of the reinforcing metal portions of the cap of one of the columns. Fig. 3 is a diagrammatical plan view, representing four columns and the metal fabric which connects the several columns of the building. Fig. 4 is a fragmental perspective view of a column and floor. Fig. 5 is an enlarged central vertical section through a column and its cap and Fig. 6 is an enlarged detail section taken on the line 6—6 of Fig. 5.

In Fig. 1, 10—10 are two of the columns of a building containing my improved con-

struction. These columns are arranged symmetrically about the building and form the vertical supporting members thereof. As diagrammatically shown in Fig. 3 these columns are preferably arranged to form squares or rectangles and are usually arranged from about 16 to 20 ft. apart, although this distance may be varied to suit the requirements. The construction of these columns is immaterial so far as my invention is concerned, but I prefer to make them out of concrete with reinforcing metal therein, and as shown in the drawings, this reinforcing metal consists of vertical bars or rods 11, to which is secured a connecting band of metal 12, which may be wound around the uprights 11 and secured thereby in any suitable manner to make a rigid frame. This frame is embedded in the concrete body 13, of the column, and the uprights 11, extend from top to bottom of the building, the uprights being made in suitable lengths and spliced together in any desirable manner.

The floor is shown at 20 and is supported upon the columns 10. Said floor comprises a concrete body 21, and metal reinforcements 22, the concrete body being united with the concrete body of the columns into one solid mass, and the metal reinforcements 22 being also connected to the metal reinforcements of the columns. As shown, these metal reinforcements consist of two layers of metal fabric 23—24 which may be ordinary wire mesh or expanded metal. It may be found desirable to use welded fabric of such widths as to cover the span between two adjacent posts, and a very desirable form of metal fabric is one in which the strands are electrically welded together, although the ordinary wire mesh now in commercial use can be used. When ordinary mesh wire is used, the strips are laid so as to overlap each other as diagrammatically shown at 23^a, in Fig. 3, and a second layer of wire mesh is laid immediately on top of the first layer and at right angles thereto and in close contact therewith. This wire mesh extends across the entire building and becomes embedded in the concrete when the construction is completed and the adjacent overlapping edges become tied together by the surrounding concrete. At a suitable distance below the wire fabric 23, is secured a second layer of wire fabric 24, which is preferably of the same construction as the metal fabric which forms the up-

per layer 23. Both layers extend across the columns and become rigidly secured thereto when the concrete is added to complete the floor.

5 When wire fabric is used in these constructions, I find that it becomes necessary to provide an enlargement or cap on the column for the floor, in order that the wire fabric may have more of the bearing upon 10 the column than it would have if no caps or enlargements were provided. I form this cap by employing two series of rods 30—31, the series 30 being preferably bent at their middle portions as shown at 33 so as to form 15 two diverging arms or ends which extend upward and outward to the fabric 24, which is near the bottom edge of the floor. This forms a sort of brace or bracket that extends out from the column under the floor. The 20 upper series of rods 31 are arranged near the upper face of the floor and are placed immediately below the metal fabric 23, so that the latter may rest upon these supporting rods. The rods 30 and 31 are connected and 25 spaced apart by means of stirrups 32, the construction and arrangement of which is clearly shown and described in an application for building construction filed by me on the 20th day of December, 1906, and given the Serial 30 Number 348,719. It is of great importance that the metal parts of these constructions be separated from each other in order that the concrete may completely surround each individual member of the metal reinforcing 35 parts so as to insure safety of the device. The two series of rods are preferably arranged in sets of five or six rods in each set, and placed at right angles to each other as indicated in Fig. 2, although this arrangement 40 of the rods is not essential to my invention, as they may be arranged in other suitable ways, as may be found desirable.

In erecting a building containing my improved construction, the frames of the 45 columns for the first floor are first put in place. Wooden molds or centers 40, are then secured in place immediately below the floor to be made, said centers or molds being supported upon trestles or the like. In general, 50 this mold forms a flat surface extending across the entire building except at the columns, where the centers are shaped to conform to the contour of the cap or bracket of the columns. Suitable molds are also provided for the column and when these are put 55 in place the columns may then be completed, by filling the column molds with concrete and ramming it in place. After the centers 40, have been placed in position, the brace 60 rods 30 and stirrups 32 are put in position, the rods 30 being placed above the molds and a layer of concrete is then spread upon the centers or molds. The wire fabric 24 is then laid upon this layer of concrete, which 65 wire fabric as above stated, is laid across the

columns from end to end of the building, and if this fabric is composed of narrow strips, a second layer is laid directly thereon and at right angles to the first layer, as shown in Fig. 3. The uprights 11 of the columns and 70 the stirrups 32, pass through the fabric thus connecting the latter to the columns. Concrete is then filled in upon the fabric up to within an inch or two of the upper face of the floor and then the cap rods 31, are placed 75 in position in the stirrups and the second layer or tier of wire fabric 23, is placed upon the body of concrete. Another layer of concrete is then filled in on top of the second layer or tier of fabric and the construction of the 80 floor is complete. The frames for the columns on the floors above may be put in place during the work on the floors, or, if desired, they may be put in place before the floor is completed. As soon as the concrete has set, 85 the centers and molds may be removed and used in erecting that part of the building above the floor so constructed.

In the ordinary construction of reinforced concrete buildings, it is customary to employ metal girders such as "I" beams and the like to support the floors, the girders being hung upon the columns or uprights of the construction. These girders not only are very heavy and add to the weight of the 95 building, but form ridges upon the lower face of the floor, that is to say, upon the ceiling of the room below, which ridges oftentimes mar the scheme of ornamentation, and when it is desired to use the building 100 as a warehouse, they are in the way of the goods or wares in case it is desired to fill up the entire space between the floor and ceiling.

In my construction, I have entirely dispensed with girders of any form, either of metal or of reinforced concrete and have not, by so dispensing with the girders, endangered the stability or the load carrying property of the structure. This I accomplish by employing a plurality of layers of light metal fabric which covers the entire floor space of the building and which metal fabric is directly connected to the metal framework of the columns and completely 110 embedded in concrete, the entire composition of concrete and metal of both columns and floors being united into one solid mass. It will be noticed that by employing a metal fabric which extends from column to 115 column and covers the entire area bounded by the columns, that when a load is applied to it at any point upon the floor, the strain will be distributed over the entire fabric and the strain will thereby be more evenly 120 distributed over all of the supporting means of the construction, and will not have to be carried by one or a few of the ordinary supporting means.

I find that in constructing a girderless 130

floor; a saving of from 30 to 40 per cent. can be had, for the reason that a great share of the cost in erecting a building of this class, is in the preparation and use of the forms 5 and centers.

I find that by dispensing with the molds or forms for the girders, this saving can be had, which saving is of course of great importance in large constructions.

10 I am aware that various alterations and modifications in the arrangement and form of the parts may be had without departing from the spirit of my invention, and I do not desire, therefore, to limit myself to the exact construction shown and described.

I claim as new and desire to secure by Letters Patent:

1. In a girderless floor construction, the combination with suitable columns, of rods 20 supported therein and extending transversely therefrom, a metal fabric extending over the entire area bounded by the columns and resting upon and connected with said rods and columns, a second metal fabric extending over the entire area bounded by the 25 columns and arranged above the first fabric and a body of concrete in which said fabric and rods are wholly embedded.

2. In a building construction, the combination with suitable columns, of diagonally disposed brace rods supported therein; a 30 layer of metal fabric resting upon said brace rods, a second series of rods arranged above the first series, stirrups connecting and separating said rods, a second layer of metal fabric resting upon said second series of rods and a body of concrete in which said parts are wholly embedded.

3. In a building construction, the combination with suitable columns, comprising uprights and metal connecting bands, of caps 40 for said columns comprising diagonal brace rods, horizontal cap rods and connecting stirrups, a floor comprising two layers of metal fabric resting upon and connected to said brace rods and cap rods and a body of concrete in which the metal parts of said columns, caps and floor are wholly embedded.

4. In a building construction, the combination with a suitable column, of a cap there-

for, comprising substantially a series of transversely extending and inclined brace rods, a second series of transversely extending rods, stirrups connecting and spacing said rods apart and a body of concrete in which all of 55 said metal parts are wholly embedded.

5. In a building construction, the combination with suitable columns, of caps therefor containing two series of transversely extending rods and spacing stirrups, and a floor 60 construction comprising substantially a plurality of layers of metal fabric, each layer resting upon one of said series of rods and a body of concrete in which all of said metal parts are wholly embedded. 65

6. In a building construction, the combination with a column containing a metal framework having suitable uprights therein, of a series of brace rods, supported in said columns, a series of cap rods above said brace 70 rods, stirrups connecting and separating said rods, two layers of metal fabric resting upon said rods and having the uprights extending therethrough and a body of concrete in which all of said metal parts are wholly embedded. 75

7. In a building construction, the combination with suitable columns, of brace rods supported therein, cap rods arranged above said brace rods, stirrups of serpentine form connecting and spacing said rods apart, two 80 layers of metal fabric supported upon said rods and a body of concrete in which all of said metal parts are wholly embedded.

8. In a building construction, the combination with suitable columns, of two or more 85 suitably separated series of transversely extending metal rods, two or more layers of metal fabric resting upon said rods, and extending over the entire area bounded by the columns and a body of concrete in which said 90 metal parts are wholly embedded.

In witness whereof I have executed the above application for Letters Patent of the United States, at Chicago, county of Cook and State of Illinois, this fifth day of January 95 1907.

EDGAR D. MARTIN.
